BALANCED HYDRAULIC PUMP OR MOTOR OF RADIAL PISTON TYPE

Julius Yarmak, Lupset, Wakefield, England, assignor to Societe Stephanoise de Constructions Mecaniques, Sainte-Etienne, France, a company of France

Application September 22, 1953, Serial No. 381,561

Claims priority, application France October 1, 1952

3 Claims. (Cl. 103—3)

This invention refers to radial piston hydraulic pumps or motors comprising a revolving cylinder block and an eccentrically located race or guide way for the pistons, which pumps or motors are adapted for infinitely variable and reversible delivery or working liquid supply such as are usually employed in hydraulic transmissions of power characterised by application of rotating and reciprocating motions.

The invention has for its main object to provide a means for hydraulic and automatic balancing of internal forces arising in such hydraulic apparatus or transmission of power and which forces resist the variation and reversing of the delivery or supply. As is well known, the forces may, in some cases, be of a very considerable magnitude thus constituting, if not balanced, an important obstacle to the proper operation of the apparatus.

According to one feature of the invention the means for providing a complete balancing and neutralizing of such resisting forces may consist of several rocking hydraulic thrusters, each comprising a cylinder with a ram and communicated continuously one by one or in pairs, or in two groups with the inlet and outlet ports respectively of the pump or motor.

The resisting forces, requiring balancing, comprise mainly an unbalanced resultant force or vectorial sum of all hydraulic forces created by liquid pressure acting on the inner ends of one part only of total number of the radial pistons of such a hydraulic apparatus and particularly the component force which is directed along the direction of displacement of the guide way for the radial pistons and of a second component force comprising friction on supports on which the guide way for the pistons thrust and reciprocate. Thus, the resisting forces in a hydraulic pump or motor, of the type concerned, depend on pressure of working liquids, on relative direction and on amount of eccentricity or displacement of the guide way for the radial pistons and on friction on their supports. All the above factors are not constant, therefore the resisting forces are changeable both in their magnitude and direction.

The balancing rocking cylinders or thrusters arranged and associated with a pump or motor according to this invention are adapted to provide forces alterable in the same way as the resisting forces of the pump or motor and, having always a direction opposite to the direction of the resisting force are able to balance or neutralize the forces completely.

A balanced hydraulic pump or motor of the radial piston type and of a variable and reversible delivery, constructed in accordance with this invention, is particularly applicable in hydraulic transmissions adapted for continuously carrying out a quick reciprocating motion of a working member of an apparatus performed by means of a hydraulic servomotor consisting of a driving piston movable in a cylinder such as is applied, for example, in the driving of a shaker conveyor troughing, for reciprocating screens, for planing and shaping machine tools and for many other machines requiring a continuous recipro-

2

cating motion of various characteristics or for a quick reversible rotating motion of other hydraulic motor.

Another object of the invention is to provide a means for a purely rolling support of radial pistons of the pump or motor to prevent hydraulic forces from acting on them and thus eliminating entirely sliding friction and avoiding loss of energy and wear.

Still another main object of the invention is to provide means of operation and such an arrangement of suction and relief valves of a variable and reversible delivery pump or motor as to enable self-adjusting of the reciprocating piston within the length of the cylinder and to prevent any possibility of fouling by the reciprocating parts connected with the piston on the stationary cylinder or parts connected with the cylinder of the hydraulic driving servomotor.

The above described main objects and features of the invention, as well as other objects and features, will readily be understood from the detailed description of 20 an example embodying the invention where a balanced hydraulic pump of the radial piston type associated with a cam mechanism is used and adapted for operation in a drive for shaker conveyors by a hydraulic transmission, which detailed description is given hereafter, referring 25 to the accompanying drawings in which:

Figure 1 is a vertical longitudinal section through the central axle of a balanced hydraulic pump, the section being taken along line 1—1 of Figure 2.

Figure 1a is a continuation of Figure 1 to the right 30 hand side.

Figure 2 is a vertical cross section along the line 2—2 of Figure 1.

Figure 3 is a cross section of the pump axle or pintle on an enlarged scale, taken along line 3—3 of Figure 1.

35 Figure 4 is a section along line 4—4 of Figure 1 showing arrangement of counter gears adapted for rotating the cams with required speed.

Figure 5 is a part section along vertical line 5—5 of Figure 2 showing both cams and the operating screw.

40 Figure 6 is a part section along vertical line 6—6 of Figure 1 showing arrangement of valves and their operating means.

The balanced hydraulic pump of the radial piston type, with reference to the drawings, comprises a cylinder 45 block 11 with several—in this case fourteen—radial holes or cylinders 12 staggered or spaced in a zig-zag manner and each housing a piston or plunger 13. The cylinder block 11 is rotatably mounted on a central immovable axle or pintle 14 by means of a bush 15 pressed into the cylinder block, and is adapted to be revolved by a coupling 16 and a shaft 17 (Figure 1a) rotatably mounted in anti-friction bearings 18 and connected with a shaft 19 of a driving motor 20 by means of cross coupling 21 comprising simultaneously a flywheel of a considerable 55 moment of inertia to equalize the speed of rotation of the motor and pump.

Each radial piston 13 is provided with a thrust roller or ring 22 adapted to thrust at one side against a concave bearing surface 12a of the piston end inside the fork 60 portion 13a and to bear at its opposite side upon the inside cylindrical thrust surface of a drum 23 comprising a race or a guide way for the pistons. The thrust roller or rings 22 are guided in grooves 11a provided in the cylinder block 11, and in the fork portion 13a of each 65 piston 13, thus preventing the pistons from turning in their cylinder holes 12. Each thrust roller or ring 22 is linked movably to the fork portion of the outside piston end by means of an axle pin 24 fixed to the fork portion 13a at the piston 13 and located in a central hole 24a 70 of a relatively large diameter provided in the roller 22.

The drum 23 is firmly attached by means of spigot portions and screws 25 to two side rings 26 and 27. Said

parts thus form together an outside rotor of the pump or motor comprising the cylindrical guide way or race for the pistons 13 and is rotatably supported by two roller bearings 28 and 29.

It may be understood that during revolution of the cylinder block 11 by a driving motor with a usual high speed, the pistons 13 together with the thrust rollers 22 will be pressed to the inside cylindrical surface of the drums 23 by centrifugal forces. It is obvious that in one particular position where the guide way or race drum 23 is concentric with the axle 14 on which the cylinder block 11 revolves, all the rollers 22 could be displaced very slightly only from the centre of the concavity of the piston ends in their fork portions 13a depending on the direction of rotation so that all axle pins 24 will become eccentric to the same relative side of the holes 24a, and therefore the rotation of the cylinder block 11 will be transmitted to the guide way drum 23 by friction forces between the thrust rollers 22 and the inside cylindrical guide surface of the drum 23. In this particular relative position of the guide way or race there will be neither any movement of the thrust rollers 22 relative to the pistons 13 nor any reciprocation of the pistons 13 relative to the cylinder block 11. All said parts will rotate around the axle 14 with the same bodily speed without any sliding friction between them and there will be no pumping action in this particular position.

It may be understood further that during rotation of the cylinder block 11 in either direction and in the position where the guide way drum 23 is displaced from the centre of the cylinder block 11, the pistons 13, being always forced out by centrifugal forces will follow the cylindrical eccentric guide way or race and, therefore, will perform one full reciprocating movement during each revolution of the cylinder block 11. During this process, the thrust rollers 22 will adjust themselves relative to the concave ends of the pistons 13 in the fork parts 13a depending on the amount of the relative eccentricity and direction of the rotation, so that the rollers 22 will roll slightly in both directions, i. e. rock or oscillate on the concave piston ends 12a in forks 13a during every revolution of the cylinder block 11 to compensate in this way for any change of distance between the piston ends and any difference in relative peripheral speed of rotation repeated during every revolution when following the inside contour of the eccentric guide way or race during the pump or motor operation.

The guide way drum 23 will be rotated with an average and constant speed by that part only of the rollers 22 which in turn are under pressure and by the tangential and friction forces in similar manner to that described above for the concentric position. The tangential forces will depend of course on the amount of displacement of the rollers relative to the piston ends. It may be noticed that there will be only rolling and no sliding friction between the concave end at the pistons 13, the rollers 22 and the drum 23, provided the clearance for the axle pin 24 in the hole 24a is adequate to cover the maximum amount of eccentricity of the guide ways for the pistons.

Both roller bearings 28 and 29 are mounted on integral collars of two side plates 30 and 31 respectively, of a rigid cradle frame which includes also two curved plates 32 and 33 (Figure 2). All said parts, forming the reciprocating cradle frame, are secured together by means of screws 34 and dowel pins 34a.

The cradle frame, as a whole, is slidably supported by means of two pairs of pads 35 and 36. The pads 35 are thrusting on and sliding across the central axle or pintle 14 and the pads 36 are thrusting on and sliding across a spigot bush 37. The curved plate 33 of the cradle frame is provided with an integral rigid tail piece 38 slidably fitted in bush 39 of a spigot flange 40 attached to side wall of housing. Therefore, the cradle frame, being supported at three points 35, 36 and 39, is able to reciprocate in a horizontal plane across the pump axle 14 to dis-

place the centre 41 of the guide way or race circle for the pistons 13 in both directions relatively to the centre 42 of the axle 14, which is also the centre of rotation for the cylinder block 11.

During revolving of the cylinder block 11, each piston 13, being always pressed to the inside cylindrical surface of the guide way drum 23 by centrifugal forces, will perform one full reciprocating movement in its cylinder hole 12 during every revolution of the cylinder block 11, and the amplitude or length of stroke of pistons 13 is always equal to the double eccentricity or double distance between two centres 41 and 42.

Inside the axle or pintle 14, comprising simultaneously a rotary type valve of the pump, as is usual for pumps of this kind, two pairs of holes 43 and 44 are provided. Holes 43 are both communicated with the flexible pipe 45 and the holes 44 are both communicated with the flexible pipe 46. Flexible pipes 45 and 46 lead to opposite sides of a driving piston in a cylinder forming a hydraulic servomotor (not shown in the drawings). Both pipes 45 and 46 may be either inlet or outlet ports of the pump or motor alternatively depending upon the direction of the eccentricity by a constant direction of the cylinder block rotation.

For a continuous alteration of the eccentricity and thus the quantity and direction of working liquid supply in one particular application case of a balanced hydraulic pump or motor, constructed according to the present invention, a cam mechanism is employed comprising a rotatable elongated disc cam 47, slidably mounted on a shaft 48 which is rotated with a required speed from the driving shaft 17 (Figure 4) by means of gears 49, 50, 51, 52, 53 and 54 arranged inside a housing 55. The cam 47 is adapted to act on a roller 56 rotatably mounted in a projecting portion of the curved plate 32 of the cradle frame. A compression spring 57 is adapted to force continuously the whole cradle frame with the roller bearings 28 and 29 and the outside rotor of the pump including guide way drum 23, against the cam 47 to perform a full reciprocation and therefore a full cycle of supply alteration of the pump during every full revolution of the cam 47.

The cam 47 comprises an elongated body of a sloping cylindrically curved shape changeable along its axis so that any cross section comprises its own working profile of a particular shape, and may be slid along its shaft 48 by means of a screw 58 provided with both right hand and left hand thread parts and mounted in a threaded bush 59 fixed at the wall of the outside housing. When rotated by means of a handle 60, the screw 58 will move itself, moving with double speed a threaded nut integral with a fork 61 engaging the collar part 62 and thus sliding the cam 47 in either direction along the shaft 48, depending on the direction of rotation of the screw 58 and changing simultaneously the actual working profile of the cam 47 which is in contact with the roller 56. In this way a characteristic of reciprocating motion may be easily altered.

The importance of all forces balancing for an easy and unrestricted movement of the cradle frame, carrying the guide way or race drum 23 in the above described cam mechanism, may be well appreciated when taking into account that the cradle frame must be in a continuous reciprocation, being under the influence of the hydraulic forces acting on one part only of the pistons 13.

Although any direct thrust from the cylinder block 11 through the bush 15 upon the axle 14 may be completely neutralized hydraulically by provision of a correct relation between the size of holes in the bush 15 and the grooves in the axle 14 so that there will be no pressure, therefore little friction and wear of these two parts. Nevertheless, the reactions to the hydraulic forces, causing the thrust of the rollers 22 at the outside ends of pistons 13 from their guide way or race, will create a very considerable vertical force because only a half of the total number of pistons 13 (i. e. only those which are either

above or below the central horizontal plane) may be under pressure. The created force is transferred through the bearings 28 and 29 to the plates 30 and 31 of the cradle frame and could cause, if not balanced, a considerable pressure, friction and resisting force between the pads 35 and 36 and their supporting means. It may be found that there exists also a horizontal force, that is, a force acting along the reciprocation direction of the cradle frame with the guide way drum 23. The force arises because of the eccentricity of the guide way or race relatively to the rotation centre of the cylinder block 11. It may be noticed that a relatively larger part of the cylinder block 11, representing therefore a relatively larger number of the radial pistons 13 under pressure, acts to resist an increase in the eccentricity of the guide way or race than those acting to assist the increase.

For a balancing of all the above described forces, there are provided four identical rocking hydraulic thrusters 63, 64, 65 and 66 (on Figure 2 one thruster 63 is shown in section and the rest are shown in outside view). Each thruster comprises a cylinder 67 with a wedge shaped thrust blade 68 and a piston or plunger 69 with its similar wedge shaped thrust blade 70. For tightness there is provided a piston ring 71. A light spring 72 is adapted to assure continuous contact between the blades 68 and 70 and their thrust pads 73, 73a, 74 and 74a in cases where the thruster is not under pressure. Two thrusting pads 74 are mounted firmly in a projecting bracket 75 forming an integral part of the curved plate 32 and bearing the thrust roller 56. Two other thrust pads 74a are mounted firmly in the tail piece 38 integral with the curved plate 33. Two thrust pads 73 are firmly and immovably mounted in beams 76 and two last thrust pads 73a are mounted immovably at the bottom of the housing.

Both upper thrusters 63 and 65 are communicated continuously in a first pair with the upper bores 43 by means of two flexible pipes 77 and 77a (Figures 2 and 6) and both lower thrusters 64 and 66 are communicated continuously in another pair with the bores 44 by means of two other flexible pipes 78 and 78a.

It may be understood from the above description that, under influence of the cam 47 and the spring 57, the cradle frame together with brackets 75 and tail piece 38 will perform a reciprocating movement so that centre 41 will be displaced alternatively to the left and to the right side in relation to the centre 42 and all four thrusters 63, 64, 65 and 66 will rock simultaneously. The relative positions of the immovable thrust pads 73 and 74 are such that when the centres 41 and 42 are in the same point (i. e. when there is no eccentricity) all thrusters are in vertical or neutral positions. The diameter of the thruster pistons 69 is of such a size that each pair of thrusters 63 and 65 or 64 and 66 will be able to balance the vertical component force of all hydraulic forces acting on pistons 13, and the length of the thrusters is such that each pair of them will be able to produce, when tilted from the vertical position, a force directed along the direction of eccentricity and of the same magnitude and increasing in the same proportion as the horizontal force resisting the displacement of the cradle frame, thus being able to balance the resisting force.

By the arrangement described above, all forces resisting the movement of the cradle frame will always be balanced hydraulically because, as may be understood, by either direction of rotation of the cylinder block 11, by any pressure of the working liquid in either bore 43 or 44 (or in both bores simultaneously) and by any eccentricity of the guide way for pistons 13, the rocking hydraulic thrusters will simultaneously and automatically provide balancing forces or counterpressures acting on the reciprocating cradle frame supporting the race which forces are equal in amount and opposite in direction to the forces resisting the displacement. Therefore, the required reciprocation of the cradle frame for variation and

change in direction of the pump supply may be performed easily and unrestrictedly.

To provide means of self-adjustment for the reciprocating driving piston within the cylinder length of the servomotor, adapted for reciprocating a shaker conveyor troughing or similar apparatus members of a considerable momentum by means of allowing a free slip of the hydraulic liquid excess which may occur on either side of the driving piston because of leakage and other casual reasons, in a balanced hydraulic pump constructed according to the invention, a rocking lever mechanism adapted for lifting suction valves synchronously with every reverse of the hydraulic servomotor stroke is arranged.

The lever mechanism is associated with the common suction and relief valves which are provided as usual in hydraulic apparatus of such a kind and are adapted to replace any leakage and other loss of liquid in the system and to act as safety means, preventing over-pressure.

In this particular case, a separate suction valve 80 or 80a with a ball 81 or 81a and a relief valve 82 with a ball 83 loaded by spring 84 regulated by a threaded plug 85 is associated with each bore 43 or 44.

Both valves 80 and 82, as may be seen on the drawing (Figure 6), are connected with the bore 44 and are both included in a separable valve block 86 that is fluid tightly secured to the axle 14 by two screws 87. Fully identical suction and relief valves are connected with the second bores 43 of the axle 14. Both last valves are included in the second separable valve block 89 secured fluid tight to the opposite side of the axle 14 by means of two screws 90.

To lift either suction valve 80 or 80a so as to keep them open during required periods of the servomotor piston stroke and each time just when direction of the piston movement is altered, two thrust screws or tappets 91 and 92 securely mounted in a rocking lever 93 are provided and are adapted for a rocking movement with an axle 94 (Figure 6). The rocking lever 93 is connected by a bar 95 and a thrust spring 96 with a second lever 97 rocking with its supporting axle 98 by means of a weight 99 and roller 100 operated by an eccentric disc cam 101 securely mounted on the same shaft 48 where the elongated cam 47 adapted for variation and change in direction of pumping is slidably mounted. The disc cam 101 (Figure 6) is provided on its working profile with two cylindrical portions 102 and 103 of such a radius as to keep both thrust screws or tappets 91 and 92 in the neutral position without reaching either of two valve balls 81 and 81a. A raised portion 104 of the disc cam is adapted to lift and keep open the valve 80 during a period when the driving piston of the servomotor is changing the direction of its movement. A lowered portion 105 of the disc cam is adapted to lift and keep open the second valve 80a when the driving piston is changing its direction of movement again. It may be understood that the suction valve, thus lifted and kept open, will prevent building up counterpressure by permitting a free escape of the hydraulic liquid from the corresponding side of the servomotor cylinder when the driving piston is changing its direction of movement and is pushed and thus adjusted nearer to the central position in the cylinder under the influence of pressure springs or other cushion means usually provided on a servomotor of that kind.

The described hydraulic pump or motor is housed inside an enclosed casing 107 provided with a cover 108 and mounted on a base plate 109 on which the driving motor 20 is mounted as well. The inside space of the casing 107 is divided into two chambers or compartments 110 and 111 by a vertical wall 112. The chamber 111 comprises the hydraulic liquid container having a high liquid level 113. As may be seen in figure 1, the central axle 14 passes through the chamber 111 from an outside wall 114 to the wall 112 by which walls the axle 14 is firmly supported. Both valve blocks 86 and 89, including

the suction and relief valves are, located in the chamber 111. The rotating parts of the pump or motor are located in the chamber 110 having a low liquid level 115. Thus, provisions are made for rotation of the pump parts, not in an oil bath, but in air, enabling a high speed of rotation because the friction between oil and rotating parts of pump, which friction at the high speed would be very considerable, is eliminated.

To keep the liquid level 115 in the room 110 at the required low height, it will be necessary to remove any excess liquid which may come from leakage during the pump operation. For that purpose, a downwardly sloping oil reflector 116, in the form of a corrugated sheet, is arranged at the top of the housing above the pump rotor. By this arrangement, any oil in excess of the level 115 will be caught by immersed rotating parts of the pump rotor, including the drum 23, and dropped continuously on the corrugated sheet or oil reflector 116 to let the excess oil flow freely back into the container 111. It may be understood that all parts inside the housing 107 will be well lubricated by oil mist and drops created by the quick rotating parts of the pump.

For the purpose of oil filling and the level inspection, there is provided a small cover 117 with a threaded plug 118 and an oil strainer 119.

The small housing 55, containing counter gears 49, 50, 51, 52, 53 and 54, is separated from the room 110 by an oil seal 120 and is secured to the housing 107 by four screws 121 and is provided with its inspection cover 122 held in position by screws 123.

It may be well understood that the pump described above will act as a motor when the hydraulic liquid will be supplied under pressure through either one of the pipes 45 or 46. Therefore, during that part of every reciprocation of the conveyor troughing (or other reciprocating parts of an apparatus) or that part of the stroke during which the troughing is accelerated, the above described hydraulic mechanism will work as a pump; supplying working liquid under pressure and transmitting the energy of the driving motor 20 and partly the kinetic energy accumulated in the speedy rotating flywheel 21 to the reciprocating troughing (or other parts), but during the next part of the conveyor stroke comprising retardation of the troughing, the hydraulic mechanism will act as a motor using working liquid under pressure and supplying energy to the flywheel and driving motor accelerating them.

It may be understood as well that in both cases when the hydraulic mechanism in acting either as a pump or as a motor, the function of the balancing arrangement as described above will be performed equally smoothly and the result of balancing will be equally important.

What I claim is:

1. In a hydraulic reversible pump of the radial piston type, which includes a cylindrical casing, a cylinder block rotatably disposed in the casing and provided with radial cylinders and pistons slidably in said cylinders; means for a purely rolling support of the radial pistons against hydraulic, centrifugal and inertia forces to which the pistons are subjected during operation of the pump, said means comprising a bifurcation provided at the outer end of each of said radial pistons, a concave cylindrical surface formed on each end of the pistons between the branches of the bifurcations, said cylindrical surface having its axis parallel to the axis of rotation of the pump, a thrust roller located between the branches of each bifurcation, each roller being interposed by opposite sides of its outer periphery between the concave surface of the pistons and the inner cylindrical guide surface of the casing, said casing being displacable eccentrically and freely rotatable, an axle pin secured in the branches of each bifurcation, each roller having a central hole re-

ceiving the pin, each of said pins being of smaller diameter than the holes to provide a movable linkage of each roller in each bifurcation thus enabling a limited oscillating rolling movement for each roller along the concave cylindrical surface of each piston and along the guide surface of the casing.

2. A hydraulic reversible pump of the radial piston type comprising a housing having outer vertical walls and an inner vertical wall, said last wall dividing the housing into two oil tight compartments, a pintle horizontally mounted in one of the outer walls and in the inner wall and passing entirely through one of the compartments and projecting into the other compartment, said pintle being provided with an upper and a lower duct, the ducts selectively serving as suction and exhaust ducts according to the direction of rotation of the pump, a cylinder block rotatably supported on the projecting end of the pintle in the other compartment, a horizontal shaft coupled to the cylinder block for rotating the block, radial cylinders provided in the cylinder block, pistons reciprocating in said cylinders, a reciprocating cradle disposed in said other compartment and mounted for movement transversely to the axis of the pintle, a guide way drum rotatably supported on the cradle for free rotation thereon and having an inner cylindrical guide surface, roller means on the outer ends of the pistons and disposed in rolling contact with the guide surface, means for continuously reciprocating the cradle to displace the drum eccentrically in two opposite directions with respect to said cylinder block for modifying the stroke of said pistons in the cylinders, two sets of balancing rocking hydraulic thrusters, one of said sets being disposed above the horizontal plane containing the axis of the pintle and the second set being disposed below said plane and between said housing and said cradle and adapted to provide forces directed substantially at right angles with respect to the direction of reciprocation of said cradle, each of said thrusters including a cylinder having an open end and a knife edged closed end, a piston sealingly and slidably fitted in each of said thruster cylinders and having a knife edged outer end, a compression spring disposed inside each thruster cylinder and bearing against the closed end of the cylinder and the inner end of the piston to extend the thruster piston, a flexible pipe connected to each thruster cylinder, the flexible pipes leading to the set of thrusters disposed above the horizontal plane of the pintle being connected with the upper duct of the pintle and the flexible pipes leading to the thrusters of the set of thrusters disposed below said horizontal plane being connected with the lower duct in said pintle.

3. A hydraulic reversible pump as claimed in claim 2, wherein a plate is disposed above said guide way drum in a sloping position from the other compartment towards the one compartment so that any leakage of oil from the pump in the other compartment is caught by the drum and centrifugally thrown on said plate and returned thereby into the one compartment.
